DESIGN FOR A SPRINKLER

John George Evans, Chicago, Ill., assignor to
W. D. Allen Manufacturing Company, Chicago,
Ill., a corporation of Illinois

Application December 12, 1935, Serial No. 60,034

Term of patent 14 years

To all whom it may concern:

Be it known that I, John George Evans, a citizen of the United States and a resident of Chicago, in the county of Cook and State of Illinois, have invented a new, original, and ornamental Design for a Sprinkler, of which the following is a specification, reference being had to the accompanying drawing, forming a part thereof.

Fig. 1 is a plan view and

Fig. 2 is a side elevation of a sprinkler embodying my new design.

The dominant features of my design reside in the portions shown in full lines.

I claim:

The ornamental design for a sprinkler, substantially as shown and described.

JOHN GEORGE EVANS.
